Primary Examiner — Patricia A Palasik(74) *Attorney, Agent, or Firm* — MacMillan, Sobanski & Todd, LLC(57) **CLAIM**

The ornamental design for a rotary actuator, as shown and described.

DESCRIPTION

FIG. 1 is a side perspective view of a rotary actuator showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the drawings depict unclaimed environmental subject matter of the rotary actuator.

The shade lines in the figures show contour and not surface ornamentation.
